MACHINE FOR MAKING CONTAINERS

William W. Van Voorhis, Antioch, Calif., assignor to Fibreboard Products, Inc., San Francisco, Calif., a corporation of Delaware

Application November 27, 1943, Serial No. 511,952

14 Claims. (Cl. 93—51)

This invention relates to machines for making nested containers of the wireless pail type and also of other types, of paperboard.

Containers can be made by folding blanks in different ways and it is often desirable to apply adhesive at suitable areas of the blanks to maintain the containers in their desired form, but a certain period of time must generally elapse before the adhesive dries or sets sufficiently to prevent unfolding of the folded blank. Such folded blanks often have the tendency before setting of the adhesive to unfold into an unsuitable form and this tendency often results in blocking the entrance of each unit in such a manner as to prevent nesting of the next unit therein. This is true of different types of containers made by folding blanks, including the full gusset pail type where the gussets are folded exteriorly of the container to which the invention is particularly applicable. It will be described with respect to such type of container with the understanding that it is applicable to other types as well. Such full gusset type is formed from a single continuous blank of material suitably scored or creased so that it can be easily folded to provide the container when the folds are held in place. The material of which the container or pail is made is generally paperboard, sometimes called cardboard or fiberboard or the like, and it is generally waxed or otherwise treated to prevent it from absorbing liquid contents or permitting such contents to leak therethrough. Full gussets have been used to prevent openings at the edges of adjoining walls of the container through which leakage could occur. Such containers are particularly well adapted for packaging bulk ice cream, cottage cheese, olives, pickles, and other materials comprising a liquid. A metal wire handle was generally used with this type of container or pail, the ends of which were connected to the gussets for holding them together. The gussets were folded exteriorly of the container so that the wire need not contact the contents, and the exterior folding also resulted in the smoothest possible interior surface.

Metal for the wire handle is not easily available at the present time, and a handle which is formed of an integral part of the container blank is set forth in the application of Charles H. Goodyear for Container, Serial No. 492,489, filed June 28, 1943, assigned to the assignee of this application. In the manufacture of full gusset pail type containers, adhesive is usually applied to certain parts which contact other parts when the blank is folded to form the container, the

adhesive when dry maintaining the container in the shape desired for use. It is expedient to nest the containers each within the preceding one to save space in manufacturing, storage and shipping, and it is convenient for the user to have the containers so nested as this makes them easily available for use.

With the containers confined to prevent portions thereof from moving outwardly or inwardly, the parts to be adhesively bound together are held in the proper juxtaposition until the adhesive has set to hold such parts firmly united. The adhesive used does not dry or set immediately, and since it does not bind the parts until it has set, the result is that the resiliency of the paperboard causes the folded blank, if it is not exteriorly confined, to open up and become nothing more than a partially folded blank. Confining the container or pail exteriorly so that it cannot open up before nesting may be done expediently within a chute or runway which furnishes at the same time a path of travel for the nested containers. But when confined exteriorly before completion of the nesting of the next succeeding unit therein, the resiliency of the material causes the sides toward which the gussets are exteriorly folded to incline inwardly of the container and thereby block the interior sufficiently to prevent nesting. All four sides of the container of the Goodyear application mentioned above, and perhaps of some other containers also, have extensions to be bent over at creases to form top flaps, and these extensions or flaps further block the openings into the containers and aggravate the difficulty of nesting of the containers before the adhesive has set.

Objects of this invention are to provide automatic means for holding the parts of the containers in such position that they can be automatically nested and means for nesting them, before the adhesive has set and without any unfolding of the parts, and other objects will be apparent after reading this specification.

Preferred exemplifications of the invention are shown on the accompanying drawings forming a part of this specification, on which

Fig. 1 is a vertical section of a machine for accomplishing the objects referred to above, with the parts in their position at an earlier stage of a cycle of operation;

Fig. 2 is a similar view at a later stage of the cycle;

Fig. 3 is a cross section on the line 3—3 on Fig. 1;

Fig. 4 is a plan view of a scored or creased flat container or pail blank;

Fig. 5 is a perspective view of a partially folded blank;

Fig. 6 is a perspective view of the container or pail showing the position its parts assume before the adhesive has set;

Fig. 7 is an elevation, with parts broken away, of a modified form of machine for accomplishing the objects referred to above, with the parts in their position at the beginning of a cycle of operation, and

Figs. 8, 9, 10 and 11 are views similar to Fig. 7 showing the parts in different positions during a cycle of operation.

Flat blanks 10, as that shown on Fig. 4, have scores or creases along all the dotted lines thereon. All dotted lines on such figure represent creases or scores and are collectively marked 11. All such scores or creases may, if desired for the sake of simplicity, be impressed into the same side of the blank simultaneously. The blanks are bent to form containers which are preferably tapered and have a rectangular bottom 12, a pair of opposite trapezoidal side walls 13, and a pair of trapezoidal side walls 14. Foldable full type gussets 15 connect the pairs of side walls 13 and 14, the material of which is continuous, and thus the container is as leakproof as the material of which it is made. The sides 13 have extensions 16 and the sides 14 have extensions 17, these extensions forming the top or cover flaps of the container on bending them at the creases or scores defining them. The flaps 16 have cuts 18 therethrough and the flaps 17 have cuts 19 therethrough. The cuts 18 are to form handle portions and the cuts 19 are to form interlocking portions. Adhesive is applied to certain parts of the flat blank 10, after which it is folded at the scores or creases. It is applied so that gussets will be held to gussets and to outer faces of side walls when the adhesive has set. The adhesive is applied preferably but not necessarily only to faces which will be outside of the finished container to avoid any chance of contamination of contents by the adhesive. For example, if the side walls and gussets are folded upwardly from the blank of Fig. 4, then the adhesive is preferably applied only to the lower face of the blank, and, if desired, only to gussets. The adhesive is preferably applied by conventional automatic means. A pail of such type is described and claimed in the Goodyear application referred to above. The gussets are folded to overlap each other against the outer faces of one of the pairs of side walls 13 or 14, preferably against the narrower pair if they are not of the same width. This allows for more printing space on the wider side walls and also affords more overlapping of the gussets. Such folding is shown on Fig. 6. The present invention is useful with respect to the Goodyear invention and other types of pails, as well as to containers generally.

The blanks having the adhesive properly applied thereto are usually located one at a time over a member having an opening therethrough functioning as a forming die which is conventionally used for folding container blanks, and is therefore not shown, with the bottom 12 properly located over such opening. A plunger moves onto the face of the bottom 12 and forces the blank through the die thereby causing it to be folded in conventional manner into a container having an open top and this to be moved into a four-sided runway in which containers with their tops open

are nested. The containers, after being folded into shape on passing through the die, are moved one by one into a chute or runway 21 having four sides 22, 23, 24 and 25, through which the series of containers is forwarded and which prevents the sides of the containers from spreading. They are nested within the runway, one at a time, each into the preceding one, as will be described hereinafter.

The plunger has a bottom member 26 dimensioned to fill the bottom of the folded container, and it is attached to a hollow cylinder 27. Attached to the bottom member by screws 28 are side members 29. The cylinder 27 has opposite openings 31 therethrough, through which levers 32 project, these levers having ends 33 shaped to contact the extensions 17 and swing them outwardly about their scores or creases, as will be referred to hereinafter. The levers 32 are pivoted on pivot pins 34 affixed to the cylinder 27. A rod 35 is mounted to slide in holes in disc bearings 36, 37 affixed to the cylinder 27 by pins 38. The lower end of the rod 35 is provided with a disc-like head or abutment 41. A compression spring 42 extends between the disc 37 and the inner ends of the levers 32 about the rod 35. A stop member 43 is affixed to a suitable stationary support 44. A cross-bar 45 is attached to the rod 35, to contact and be stopped by the stop member 43. The cylinder 27 is reciprocated to form the containers consecutively, and the plunger 26 as well as the rod 35 and parts appurtenant thereto reciprocate with it.

The parts of the formed blank, tend to assume, if not confined, before the adhesive has set, the positions illustrated in a general way on Fig. 6, the walls 14 and the extensions or flaps 17 thereon preventing nesting of another unit therein. On its downward movement, the plunger gathers a blank as shown on Fig. 4, to suitable parts of which adhesive has been applied, about itself by pressing the blank through the die which per se forms no part of this invention. The plunger is then within the shaped container in the position shown on Fig. 1, the applied adhesive having not yet set, nor has the adhesive set on the next preceding unit. As the cylinder and plunger continue their downward movement to the position shown on Fig. 2, the plunger carries the containers along with it. The rod 35 and the cross-bar 45 move downwardly with the cylinder 27 and plunger until the cross-bar is stopped by the stop member 43, the cylinder 27 continuing its downward movement to compress the spring 42 and thereby cause the pivot pins 34 to approach the abutment 41. Due to the shape of the levers 32, they are thereby forced outwardly as shown on Fig. 2 to press the flaps 17 outwardly.

The sides 22 and 23 of the runway have opposite site openings 46 therein respectively, at the position where the levers 32 move outwardly. Hooks 47 which are preferably resilient, are attached by screws 48 or any other suitable fastening means to the walls 22, 23, in such position that the flaps 17 are pushed under the hooks by the end 33 of the levers 32 when the levers are moved outwardly as shown on Fig. 2. By this time the container on the plunger has entered and has been nested within the container next preceding it by the continued downward movement of the plunger, as shown at the lower half of Fig. 1. The hooks 47 retain the container and strip it from the plunger on the upstroke thereof, and by preventing the flap portions 17 from moving inwardly, permit nesting of the next con-

tainer formed by the next downstroke of the plunger.

Nesting is aided by ribs 49 on the inner faces of the runway sides 24 and 25 which exert pressure on the walls 13 of the container which causes them to bend inwardly as shown on Fig. 3, which in turn causes the side walls 14 to extend outwardly away from each other. This assures that the walls 14 and the flaps 17 will be extended outwardly to be in proper position so that the flaps 17 will be extended outwardly under the hooks 47. The container parts would otherwise assume the positions shown on Fig. 6.

When the plunger is at the lowermost part of its downstroke, it begins its upstroke and leaves the container which is thereon, before its adhesive thereon has set, within the next preceding one and thereby prevents such preceding one from collapsing and the parts thereof from moving inwardly. The last container in the nest is held open by the hooks 47. The chute or runway 21 extends to a desired point of delivery and the nest of containers is intermittently and regularly moved forward therein to such point.

In the modification shown on Figs. 7-11, the plunger 61 pushes blanks like that illustrated on Fig. 4, with adhesive applied at the desired parts of the surface thereof, through the forming die (not shown). The plunger does this on its upstrokes and then moves the folded blank thereon upwardly into and through a runway or chute 62, in which nesting occurs. This chute may be similar to that referred to above, and is rectangular and dimensioned so that the folded containers can move therethrough. Opposite sides 63 have openings 64 therein, adjacent which endless chains or other flexible driving means 65 are mounted. Each chain runs over its own set of sprockets 66, 67, and 68. Each chain is provided with lugs 69 which project outwardly from the chains. On their travel from the sprockets 67 to the sprockets 66, the lugs 69 each project toward an opposite lug 69 on the other chain and are so positioned that they contact the lower edges of the last folded blank to lift it up and away from the plunger 61 as will be referred to hereinafter. Lugs 70 project forwardly at right angles to the lugs 69 for a purpose referred to hereinafter.

Vertically reciprocating blocks 71, the means to reciprocate which are not shown, carry pivot pins 72 on which short arms 73 can oscillate. The reciprocating blocks are behind, and the pivot pins project through, elongated openings 74 in, guard plates 74a. Carried by such short arms are two sets of arms, 75 and 76. The arms 75 project exteriorly of the chute or runway 62, before the front 77 thereof, while the arms 76 normally extend into the runway through the openings 64 in the sides 63. The arms 76 which extend into the runway may be broad.

The operation of this modification will now be described. With the parts as shown on Fig. 7, the plunger 61 has moved upwardly to the uppermost position of its stroke with a blank folded thereon at 78 after the blank has been moved through the forming die (not shown), whereupon lugs 69 by their upward movement lift the folded blank 78 off of the plunger and carry it upwardly. At the same time, the reciprocating blocks 71 are moving downwardly to complete the last half of their downstroke. When such downstroke has been completed, the parts will be positioned as shown on Fig. 8. The blocks 71 and the lugs 69 with the folded blank thereon 75

then both move upwardly. At the end of the upstroke of the blocks, the parts will be positioned as shown on Fig. 9. The folded blank then contacts the arms 76 to cause them, as well as the arms 73 and 75 to swing outwardly as shown on Fig. 10. The folded blank 78 on which the adhesive has not yet set is continuously moved upwardly within the runway progressively as shown in Figs. 7, 8, 9 and 10. As it is ready to enter the next preceding folded blank 79, on which the adhesive has not yet set, the arms 76 extend the sides 14, or rather the flaps 17 thereof, which normally tend to assume the position shown in Fig. 6, so that the folded blank 78 may enter and be nested therein, the arms 76 functioning something like a shoehorn. The folded blank 79 is maintained with its parts in correct position until the adhesive thereon has set by the unit 78 therein and by the runway. When the folded blank 78 has entered the next preceding folded blank 79 sufficiently to assure proper nesting, the blocks 71 begin their downward movement, which, together with the upward movement of the chains 65, causes the arms 75 and the lugs 70 to contact each other. The continued upward movement of such lugs and the downward movement of the blocks 71 cause the arms 75 to spread apart as shown on Fig. 11, such spreading of the arms 75 causing the arms 76 to spread apart likewise and to be removed from the interior of the unit 79 and from the interior of the runway, as shown on Fig. 11. This leaves the runway free for the next succeeding folded blank to pass therethrough and to become the element 78 for the next cycle of operation, the one which had just been the element 78 becoming the element 79. The operation shown on Fig. 11 is intermediate between that shown on Figs. 7 and 8. The cycle of operation is then repeated successively until the desired number of containers have been formed. Ribs 80 which are similar to, and have the same function as, the ribs 49 on Fig. 1 are useful also in this exemplification.

The stack of nested containers, no matter by which machine it is made, can be delivered to any desired point through an open four-sided runway 81, each addition to the nested series moving the series one step further. The invention is well adapted for making and nesting containers having the specific structure described and claimed in the Goodyear application mentioned above, and it is also well adapted for making containers generally, of any structure where there is a tendency for the formed blank having unset adhesive thereon to become distorted sufficiently to interfere with proper nesting.

Maintenance of nested units in the runway for a time sufficient for the adhesive to dry or set completes the manufacture thereof.

Some of the specific features referred to for the purpose of illustrating and describing the invention may be varied without departing from the spirit thereof.

I claim:

1. A machine for making containers, having means comprising a reciprocative plunger for forming container blanks successively into container form, a runway into which said plunger moves on its forming stroke to insert the container forms thereinto and nest them therein, and means to maintain open the form of the container immediately preceding that being nested.

2. A machine for making and nesting containers from successive container blanks, parts form-

ing opposite sides of said containers have a tendency to spring out of position before adhesive thereon has set, which comprises means to form successive container blanks into container forms which have unset adhesive thereon to bind the blank parts when the adhesive has set, a runway to receive successively formed nested containers from said forming means, and means cooperating with the runway to cause the sides between said opposite sides to bend inwardly and thereby prevent the container parts forming said opposite sides from springing out of position.

3. A machine for making containers, having means comprising a reciprocative plunger for forming container blanks successively into container form, a runway into which said plunger moves on its forming stroke to insert the container forms thereinto and nest them therein, means to maintain open the form of the container immediately preceding that being nested, and means to retain said container form on the return stroke of said plunger.

4. A machine for making containers having a tendency for opposite sides thereof to move inwardly before adhesive thereon has set, comprising a runway for nested containers, and means to cause sides between said first mentioned sides to bend slightly inwardly and thereby prevent such first mentioned sides from moving inwardly.

5. A machine for making containers having a tendency for opposite sides thereof to move inwardly before adhesive thereon has set, comprising a runway for nested containers, and means within said runway to cause sides between said first mentioned sides to bend slightly inwardly and thereby prevent such first mentioned sides from moving inwardly.

6. A machine for making containers having a tendency for opposite sides thereof to move inwardly before adhesive thereon has set, comprising a runway for nested containers, and a rib within and longitudinally of said runway to cause sides between said first mentioned sides to bend slightly inwardly and thereby prevent said first mentioned sides from moving inwardly.

7. A machine for forming and nesting containers of the type having sides and cover flaps formed from foldable blank material, comprising a runway for holding a group of such containers in nested condition, plunger mechanism mounted for reciprocating movement in the runway and movable in one direction to nest such containers by insertion of a formed container thereon into a container of said nested group immediately preceding such formed container, and opposite hooks cooperating with the runway to engage over opposite cover flaps on a container to hold said flaps out of the way during the nesting and also to hold said nested group in position when the plunger mechanism moves in an opposite direction on its return stroke.

8. A machine for forming and nesting containers of the type having sides and cover flaps formed from foldable blank material, comprising a runway for holding a group of such containers in nested condition, plunger mechanism mounted for reciprocating movement in the runway and movable in one direction to nest such containers by insertion of a formed container thereon into a container of said nested group immediately preceding such formed container, opposite hooks cooperating with the runway to engage over opposite cover flaps on a container to hold said flaps out of the way during the nesting

and also to hold said nested group in position when the plunger mechanism moves in an opposite direction on its return stroke, and means to effect relative lateral movement between the hooks and said opposite cover flaps during the nesting.

9. A machine for forming and nesting containers of the type having sides and cover flaps formed from foldable blank material, comprising a runway for holding a group of such containers in nested condition, plunger mechanism mounted for reciprocating movement in the runway and movable in one direction to nest such containers by insertion of a formed container thereon into a container of said nested group immediately preceding such formed container, opposite hooks cooperating with the runway to engage over opposite cover flaps on a container to hold said flaps out of the way during the nesting and also to hold said nested group in position when the plunger mechanism moves in an opposite direction on its return stroke, and members mounted for movement with the plunger mechanism and which are also movable laterally outwardly relative to the plunger mechanism during the nesting to move said flaps laterally outwardly.

10. A machine for forming and nesting containers of the type having sides and cover flaps formed from foldable blank material, comprising a runway for holding a group of such containers in nested condition, plunger mechanism mounted for reciprocating movement in the runway and movable in one direction to nest such containers by insertion of a formed container thereon into a container of said nested group immediately preceding such formed container, opposite hooks cooperating with the runway to engage over opposite cover flaps on a container to hold said flaps out of the way during the nesting and also to hold said nested group in position when the plunger mechanism moves in an opposite direction on its return stroke, and members mounted for movement with the plunger mechanism and which are also movable laterally outwardly relative to the plunger mechanism during the nesting to move said flaps laterally outwardly.

11. A machine for forming and nesting containers of the type having sides and cover flaps formed from foldable blank material, comprising a runway for holding a group of such containers in nested condition, plunger mechanism mounted for reciprocating movement in the runway and movable in one direction to nest such containers by insertion of a formed container thereon into a container of said nested group immediately preceding such formed container, opposite hooks cooperating with the runway to engage over opposite cover flaps on a container to hold said flaps out of the way during the nesting and also to hold said nested group in position when the plunger mechanism moves in an opposite direction on its return stroke, and members mounted for movement with the plunger mechanism and which are also pivotally supported thereby for lateral outward movement relative to the plunger mechanism during the nesting to move said flaps laterally outwardly, and means for automatically moving said members during the nesting.

12. A machine for forming and nesting containers of the type having sides and cover flaps formed from foldable blank material, comprising a runway for holding a group of such containers in nested condition, plunger mechanism mounted for reciprocating movement in the runway and movable in one direction to nest such containers by insertion of a formed container thereon into a container of said nested group immediately preceding such formed container, and opposite hooks 10 cooperating with the runway to engage over opposite cover flaps on a container to hold said flaps out of the way during the nesting and also to hold said nested group in position when the plunger mechanism moves in an opposite direction on its 15 return stroke, said hooks being mounted at the outside of said runway and the runway having opposite apertures adjacent the hooks.

13. A machine for forming and nesting containers of the type having sides and cover flaps formed from foldable blank material in which parts forming opposite sides of such containers have a tendency to spring out of position before adhesive thereon has set, comprising a runway for holding a plurality of such containers in nested condition, plunger mechanism mounted for reciprocating movement in the runway and movable in one direction to nest such containers by in- 20

sertion of a formed container thereon into a container of said nested group immediately preceding such formed container, means to cause the sides between said opposite sides to bend inwardly during the nesting and thereby prevent the parts forming said opposite sides from springing out of position and interfering with the nesting, and means to hold the cover flaps on said opposite sides out of the way during such nesting.

14. A machine for forming and nesting containers of the type having sides and cover flaps formed from foldable blank material in which parts forming opposite sides of such containers have a tendency to spring out of position before adhesive thereon has set, comprising a runway for holding a plurality of such containers in nested condition, means to nest such containers by insertion of a formed container into a container of said nested group immediately preceding such formed container, and means within the runway located at the position where the nesting is effected to cause the sides between said opposite sides to bend inwardly during the nesting and thereby prevent the parts forming said opposite sides from springing out of position and interfering with the nesting.

WILLIAM W. VAN VOORHIS.
